UNITED STATES PATENT OFFICE.

WILLIAM A. LORENZ, OF HARTFORD, CONNECTICUT, ASSIGNOR, BY MESNE ASSIGNMENTS, TO THE OTAKA FABRIC COMPANY, OF HARTFORD, CONNECTICUT, A CORPORATION OF CONNECTICUT.

WEB-FOLDING MACHINE.

Application filed June 13, 1923. Serial No. 645,202.

This invention relates to the longitudinal folding of a paper web.

One of the main features of the invention is the production of two folds along the web, whereby it may be narrowed to about one-third of its original width, the folds being reverse, so that the side portions fold against the opposite sides of the middle portion of the web. This gives the web a fan-fold or zigzag appearance when viewed endwise. One or both of the side edges of the folded web, preferably both, overlap or project from the folded web. For example, the width of one fold may be about 35% of the width of the web, the width of the other fold may be also 35%, and the width of the web between the fold creases may be 30%, thus leaving edges or borders projecting from the sides of the folded web, the width 20 of each projecting border being 5% of the original width of the web. The web, so folded, may be severed into short lengths to form paper towels, napkins and other devices. If desired, simultaneously with the 25 cutting, each towel may be provided with transverse flutes to form ornamental borders.

There is herein disclosed a machine for folding a web of paper continuously into a triple or three-ply fan-folded web, each edge overlapping or projecting beyond the middle portion of the folded web. There are employed for this purpose horizontal feeding-in or drawing rolls at the intake side of the machine. The web advancing from said rolls is bent downwardly by an inclined angular folding-apron, plate or former, which is placed substantially at one side of or offset from the longitudinal center of the web. Said former has one prolonged angular edge to extend to the remote edge of the web, and one short angular edge to extend to the near edge of the web. The apex of this former is bent in a curve and extends between vertical guiding rolls; the folded web at this stage traveling in a vertical plane. From said guiding rolls the folded web consisting of a narrow flap and a broad flap (or having a low edge and a high edge), is led over an obliquely-placed angular former plate arranged on edge, the wide end of the plate standing vertically near said guiding rolls. This second former plate is placed obliquely to the longitudinal center of the web, and

guides the paper from said guiding rolls to a pair of creasing and feeding rolls, which 55 are placed horizontally or at right angles to said pair of guiding rolls; the doubly-folded web having at this time assumed a horizontal position. As the paper emerges from the pair of vertical guiding rolls, the broad flap 60 of the web bears against the second triangular former plate, and the upper edge portion of said broad flap folds down over the top angular edge of said plate; while the opposite portion of the web folds over the 65 lower edge of the former plate. This operation results in a triple-ply web having two single-ply projecting edges; the central portion of the web being narrower than the folded portions thereof. The web is then 70 folded unequally at two edges. It is believed to be broadly new to use the disclosed former plates for producing a triple-ply fan-folded web whether with or without overlapping edges, and to offset the longitudinal 75 center or crease of the folded paper, preparatory to making a second fold by means of a longitudinally central folding apron.

From the pair of horizontal creasing and feeding rolls, the folded web proceeds to the 80 cutting rolls, which are provided with embossing or corrugating dies to ornament the paper along the lines of severance.

Other features and advantages will hereinafter appear.

In the accompanying drawings,

Figure 1 is a plan of one form of a folding and embossing machine for carrying out the present improvements.

Figure 2 is a sectional side elevation of 90 the same.

Figure 3 is a plan of a folded towel or napkin produced by said machine.

Figure 4 shows the edgewise zigzag appearance of the folded napkin at Figure 3. 95

Figure 5 is a side edge view of Figure 3.

Figure 6 shows the towel opened out.

Figure 7 is a perspective to illustrate diagrammatically the production of the second or reverse longitudinal fold in the web, 100 leaving the portion of the web between the fold creases narrower than the side folds.

Figure 8 is a sectional detail of web-severing and fluting or embossing rolls.

The web 10 is led in between feeding couples comprising each an upper roll 11 and

a lower roll 12; the latter having pinions 13 to mesh with driving wheel 14, connected to pulley 15.

The web is delivered by these rolls to a 5 folding device in the form of an angular plate 16, which inclines downwardly away from the rolls, as at Figure 2, the sides of the plate converging, as at Figure 1, whereby the web is longitudinally folded, the 10 crease being indicated at line 18, Figure 1. This line bisects the angle formed by the converging side edges of the plate. It will be seen at Figure 1 that this axis 18 is much nearer side edge 19 of the web than it is to the other side edge 20; or, in other words, the angular former plate is offset substantially from the longitudinal center line of the web. If nothing further were done to the web it would thus have one crease line 17 offset from the center line of the web, which would thus be comprised of a narrow flap 21 and a wide flap 22. It will be noted that the crease or fold is produced partly by the former plate 16 and partly by the 15 aid of a pair of vertical guiding rolls 23 placed at the apex of the angle of the former plate 16.

The upper angular edge of former plate 16, at Figure 1, may be prolonged or extended back at 24 nearly far enough to intersect one side edge 20 of the incoming web, so that at this side of the web the folding operation may be initiated as soon as the web leaves the feeding rolls 11, 12, as at 20 25. At its extended portion 24, the angle plate may be made of full width, so that it may support and guide the side portion 19 of the web to the point where it begins to fold at 26 over the lower or short angular side 25 30 of the former. This former may be supported by an overhanging cross-bar 28, mounted upon posts 29; a stud 30 depending from the bar and carrying a bracket 31 to which the former plate 16 is riveted.

45 The web, reduced in width about one-third by this offset folding, now passes to a second angular former for making a second fold, having a reverse relation to the first. The intake end of this second folding former or device is designated as 32. The plate is arranged on edge, and has upper and lower angular side edges 33, 34, converging to produce the second fold in the web. The unfolded side of the web lies against this 50 second former plate, the reverse face of which is seen at 35 in dotted lines at Figure 1. This plate extends diagonally from right to left towards the bottom portion of Figure 1. The plate 35 is carried by a bracket 55 60 36 projecting from the side of a post 37, and tapers from its broad end, near the delivery side of the vertical rolls 23, to its apex in the bight of a pair of horizontal creasing and feeding rolls 38. The axial line of the second former 35 is slightly below the pre-

viously folded up edge 26 of the web. Said plate or former 35 is placed at such a point that the new crease will be equidistant from but on the opposite side of the original central line of the web from the crease 17. The 70 folding of the web by means of the former 35 proceeds the same as if the narrowed web were single ply; and the edge 26 gradually draws or curls away from the main body of the web. Owing to the position of the 75 second former 35, and the creasing rolls 38, the final fold line or crease 39 is so placed that a border 40 on the folded web projects beyond the fold line 17, thereby overlapping the folded web, which therefore has a relatively narrow central portion between relatively broad folds on each of its faces or sides, Figure 4.

The folded web may be divided into appropriate lengths by means of a pair of 80 severing rolls 41, 42, geared at 43 to the creasing and feeding rolls 38, and driven by a pulley 44 or otherwise. The cutting is done by a knife blade 45 on one cylinder to co-operate with a grooved portion 46 on the other cylinder. Preferably each section severed from the web is simultaneously given an ornamental embossing by means of ribbed dies 47, one on each side of the knife 45, and corresponding grooved dies 48 on the 85 other roll, Figure 8. These dies corrugate the edge portions of the folded severed sections, as seen at 49, Figure 3, the corrugations going through all three plies. The length of a section severed from the folded 90 web may be substantially less than the length of the opened-out towel, as at Figure 6, so that the ornamental border or fluting 49 extends longitudinally of the towel.

Variations may be resorted to within the 105 scope of the invention, and portions of the improvements may be used without others.

Having thus described my invention, I claim:

1. A web-folding machine comprising an 110 angular former substantially offset from the middle line of the web to produce a fold, of which one flap is substantially narrower than the other, guiding rolls at the apex of said former, a second former to produce a 115 reverse fold in the broad portion of the folded web, the second former having its broad end extending along said guiding rolls, a pair of feeding rolls at the apex 120 of the second former and arranged at right angles to rolls in the first pair, a pair of cutting rolls to sever the folded web into sections, and means for embossing the folded web along the lines of severance.

2. A web-folding machine comprising an 125 angular former substantially offset from the middle line of the web to produce a fold, of which one flap is substantially narrower than the other, guiding rolls at the apex of said former, a second former to produce a 130

reverse fold in the broad portion of the folded web, the second former having its broad end extending along said guiding rolls, a pair of feeding rolls at the apex of the second former and arranged at right angles to rolls in the first pair, and transverse cutting rolls for severing the web into sections, one cutting roll having a knife and provided on each side of the knife with embossing dies extending along the knife, and the other roll having co-operating parts for cutting and embossing the web.

3. Apparatus for folding a web continuously into a three-ply fan-folded web, with each edge overlapping or projecting beyond the middle portion of the folded web, comprising horizontal feeding rolls and an inclined angular fold-producing former, with its broad end extending along said feeding

rolls, said former substantially offset from the longitudinal center of the fan-folded web, and having a prolonged angular edge to extend to the remote edge of the web, vertical guiding rolls at the apex of said former, a second angular fold-producing former placed obliquely with its broad edge extending along said vertical guiding rolls, a horizontal pair of feeding rolls at the apex of the second former, said parts so placed that as the web emerges from the pair of vertical guiding rolls, its broad flap bears against the second angular former, and the upper edge portion of said broad flap folds around the narrowing portions of said second former, and cutting rolls provided with embossing dies to ornament the paper along the lines of severance.

WILLIAM A. LORENZ.
